UNITED STATES PATENT OFFICE.

WILLIAM RUNGE, OF SENECA FALLS, NEW YORK, ASSIGNOR TO THE SENECA FALLS MANUFACTURING COMPANY, OF SENECA FALLS, NEW YORK, A CORPORATION OF NEW YORK.

GEARING FOR MACHINE-TOOLS.

No. 831,379.

Specification of Letters Patent.

Patented Sept. 18, 1906.

Application filed February 8, 1906. Serial No. 300,095.

To all whom it may concern:

Be it known that I, WILLIAM RUNGE, of Seneca Falls, in the county of Seneca and State of New York, have invented a certain 5 new and useful Gearing for Machine-Tools, of which the following is a specification.

My invention has for its object the production of a gearing for machine-tools which is particularly simple in construction and highly 10 efficient in use; and to this end it consists in the novel combinations and constructions hereinafter set forth and claimed.

In describing this invention reference is had to the accompanying drawings, in which 15 like characters designate corresponding parts in all the views.

Figure 1 is a plan of the head-stock of a lathe embodying my invention. Fig. 2 is an enlarged sectional view on line A A, Fig. 1. 20 Fig. 3 is a sectional view, partly broken away and in elevation, on line B B, Fig. 2. Fig. 4 is a fragmentary view of the head-stock. Fig. 5 is an elevation looking to the right of parts seen in Fig. 4. Fig. 6 is a plan of the operating member, the carriage, and parts associated therewith. Fig. 7 is an end view of a portion of the detached operating member. Fig. 8 is an end view of the detached carriage.

This invention comprises a cone of gears 1, 30 a tumbler-gear 2 for coöperating with the cone of gears, a shifting frame 3, connected to the tumbler-gear, means for moving the shifting frame in a direction at an angle to the axis of the cone of gears, and thereby 35 forcing the tumbler-gear into and out of engagement with any one of the gears 1, and means for moving the shifting frame and the tumbler-gear along the cone of gears.

As illustrated, my invention is embodied 40 in the head-stock of a lathe comprising a live spindle 4 and driving and speed-varying gearing 5; but as the parts 4 and 5 form no feature of my present invention description thereof is deemed unnecessary.

45 The cone of gears 1 transmits motion to suitable gearing for rotating a driven shaft, as the lead-screw. (Not shown.) Such gearing, including gears 6, 7, and 8, Fig. 3, which mesh with some of the gears 1, are loosely mounted 50 on a shaft 9 and may be locked to said shaft by any desirable means.

As seen in Fig. 2, the tumbler-gear 2 is driven by a gear 10, which is slidably mounted on a shaft 11 and is shiftable with the tumbler-gear 2. Said shaft 11 is arranged substantially parallel to the axis of the cone of gears 1 and is actuated from the live spindle 4 in reverse directions by suitable gearing, including gears 12 and 13, Fig. 3, which are loosely mounted on the shaft 11 and may be alternately locked thereto by a clutch 14. The shifting frame 3, which may be of any desirable form, size, and construction, is preferably provided with helical teeth 15, is supported on the shaft 11, and is adapted to rock 65 thereon at an angle to the axis of the cone of gears 1 for moving the tumbler-gear into and out of engagement with said cone of gears. Usually the head-stock is inclosed in a suitable case 16, which is formed with a slot 17, 70 Fig. 4, extending substantially parallel to the axis of the cone of gears 1, and with sockets 18, provided along the slot 17 and corresponding to the gears 1, the number of the sockets being generally one less than the number of 75 the gears 1. These sockets 18 are preferably provided in the exposed edge of a removable plate 19, forming part of the top of the case 16. The plate 19 and the contiguous portion of the top of the case are provided with an 80 inner bearing-face 20, spaced apart from the teeth 15 of the shifting frame 3.

In the illustrated embodiment of my invention the shifting frame 3 is rocked on the shaft 11 by a rotary worm 21, which is arranged between the teeth 15 and the bearing-face 20, with its axis at an angle to the cone of gears 1, is engaged with said teeth, and is actuated by a rotary operating member 22, including a stem extending axially through the 90 worm and journaled in a carriage 23 and a slide 24, said stem being movable axially relatively to the worm and connected thereto by any suitable means, as a key. As the operating member 22 is rotated in reverse directions 95 the shifting frame 3 is correspondingly rocked on its axis and the tumbler-gear 2 is moved into and out of engagement with the predetermined gear 1.

Rotation of the operating member 22, 100 serving to force the tumbler-gear into operative position, is limited by suitable means,

as a pin 25 on the carriage 23 and a shoulder 26 on the operating member 22, the pin 25 being engaged by the shoulder 26 at the time the tumbler-gear is in operative engagement 5 with one of the gears 1. Rotation of the operating member in the opposite direction is limited by any desirable means, as a stop 27, provided on the carriage 23 and projecting into an annular groove 28 in the operating 10 member, and a shoulder 29, provided on the operating member 22 and movable into engagement with a face 30, Fig. 8, of said stop. As best seen in Fig. 2, the shoulder 29 is normally at one side of its position assumed 15 when engaged with the face 30 of the stop 27; but during the rotary movement of the operating member 22 for bringing said shoulder 29 into engagement with the face 30 of the stop 27 the operating member is moved axially by any suitable means, as a cam-face 31, 20 coacting with the pin 25. A spring 32 serves to move the operating member axially in the reverse direction when said member 22 is rotated in a direction for bringing the face 26 25 into engagement with the pin 25. When the operating member is in its position assumed during the engagement of the tumbler-gear with one of the gears 1, the shoulder 29 is in engagement with an inner face of the stop 27 30 and serves to prevent endwise movement of the operating member against the action of the spring 32. On the contrary, when the operating member 22 has been moved to engage its shoulder 29 with the face 30 of the 35 stop 27 a passage 33, extending lengthwise in the member 22 and opening through one side of the groove 28, is alined with the stop 27 for permitting additional endwise movement of the operating member. To those skilled 40 in the art it will be understood that the tumbler-gear is easily forced into operative position and is firmly held in such position.

In the preferable construction of my invention the carriage 23 is guided by the case 16, 45 being shown as extended into and guided by the slot 17 and as provided with a rib 34, guided in a way or groove 35, formed in the inner face of the plate 19. The carriage thus moves in a direction substantially parallel to 50 the axis of the cone of gears 1. Movement of the carriage is prevented by any suitable means, as a locking-bolt 36, movable endwise relatively to the carriage and projecting into one of the sockets 18. Said locking-bolt is 55 formed with a tongue 37, projecting into and fitting the annular groove 28, this tongue being of less depth than the groove in order to permit the shoulder 29 to move past said tongue during the rotation of the operating 60 member.

When it is desired to withdraw the locking-bolt 36 from operative position, the member 22 is rotated until its shoulder 29 is in engagement with the face 30 of the stop 27, thus

alining the passage 33 with such stop. The 65 operating member may then be additionally moved axially sufficiently to withdraw the locking-bolt from the socket 18 coacting therewith, whereupon the carriage 23, the operating member 22, and the tumbler-gear 70 2 may be shifted along the cone of gears 1 to the desired position. When the operating member is released, the spring 32 will move the same axially and cause the locking-bolt to enter the socket 18 alined therewith, thus 75 preventing further movement of the carriage. 75

To those skilled in the art it will be apparent that the stop 27 when within the passage 33 coacts with the walls of such passage to lock the operating member from rotation and 80 that it is impossible to rotate the operating member for moving the tumbler-gear into and out of engagement with the gears 1 while said member is in the position assumed during the movement of the carriage and the 85 tumbler-gear along the gears 1. The carriage 23 is usually provided with an indicator 38, coacting with an index-plate 39 for informing the operator of the particular speed or feed for which the machine is set. 90

The slide 24 bears against the face 20 and is held from downward movement by the engagement of the worm 21 with the teeth of the shifting frame 3. Said slide is movable relatively to the carriage 23, being guided in 95 an opening 40 in the carriage extending in a direction at an angle to the axis of the gears 1. The lower portion of the slide 24 is formed with a lengthwise opening, which receives and closely fits the upper portion of 100 the frame 3, Fig. 3, and consequently when the slide is moved lengthwise of the axis of the cone of gears 1 the frame 3 is moved in the same direction with said slide. A suitable projection 41 is provided on the slide 24 105 and is movable in a camway 42, formed in the inner face of the plate 19, said projection being usually journaled in the slide in order to have a turning movement relatively thereto to prevent binding of the parts. As the operating member and the carriage move along the cone of gears 1 the slide 24 and the worm 21 move with said operating member and carriage and also move at an angle to the direction of movement of said carriage, thus 115 shifting the frame 3 and the tumbler-gear 2 along the gears 1 and simultaneously rocking the shifting frame and the tumbler-gear, so that irrespective of the position of the gear 2 the rotary movement of the operating 120 member will be sufficient to engage the tumbler-gear with the gear 1 alined therewith. 120

The construction and operation of my invention will now be readily understood upon reference to the foregoing description and the 125 accompanying drawings.

What I claim is—

1. In a gearing for machine-tools, a cone of

gears, a tumbler-gear for coöperating with the cone of gears, a shifting frame connected to the tumbler-gear, a rotary operating member arranged with its axis at an angle to the cone of gears, and means, between the shifting frame and the operating member, for moving the frame toward and from the axis of the cone of gears, substantially as and for the purpose described.

10 2. In a gearing for machine-tools, a cone of gears, a tumbler-gear for coöoperating with the cone of gears, a shifting frame connected to the tumbler-gear, a rotary operating member arranged with its axis at an angle to the cone of gears, means, between the shifting frame and the operating member, for moving the frame toward and from the axis of the cone of gears, and means for limiting the rotation of the operating member in one direction, substantially as and for the purpose set forth.

15

20

3. In a gearing for machine-tools, a cone of gears, a tumbler-gear for coöperating with the cone of gears, a shifting frame connected to the tumbler-gear, a rotary operating member, means, between the shifting-frame and the operating member, for moving the frame relatively to the cone of gears, a stop, and means for coacting with the stop to limit the rotation of the operating member in one direction, the last-mentioned means being movable into and out of position to coact with the stop to limit such rotation, substantially as and for the purpose specified.

35 4. In a gearing for machine-tools, a cone of gears, a tumbler-gear for coöperating with the cone of gears, a shifting frame connected to the tumbler-gear, a rotary operating member, means, between the shifting frame and
40 the operating member, for moving the frame relatively to the cone of gears, means for limiting the rotation of the operating member in one direction, a stop, and means for coacting with the stop to limit the rotation of the operating member in the opposite direction, the last-mentioned means being movable into and out of position to coact with the stop to limit the rotation of the operating member in said opposite direction, substantially as and for
45 5. the purpose described.

5. In a gearing for machine-tools, a cone of gears, a tumbler-gear for coöoperating with the cone of gears, a shifting frame connected to the tumbler-gear, a rotary operating member, means, between the shifting frame and the operating member, for moving the frame relatively to the cone of gears, a stop, means for coacting with the stop to limit the rotation of the operating member in one direction, the last-mentioned means being movable into and out of position to coact with the stop to limit such rotation, and means for moving the operating member axially to bring said last-mentioned means into position to coact

with the stop to limit such rotation, substantially as and for the purpose set forth.

6. In a gearing for machine-tools, a cone of gears, a tumbler-gear for coöperating with the cone of gears, a shifting frame connected to the tumbler-gear, a rotary operating member, 70 means, between the shifting frame and the operating member for moving the frame relatively to the cone of gears, a stop, means for coacting with the stop to limit the rotation of the operating member in one direction, the 75 last-mentioned means being movable into and out of position to coact with the stop to limit such rotation, and means for moving the operating member axially relatively to the shifting frame to bring said last-mentioned means into position to coact with the stop to limit such rotation, substantially as 80 and for the purpose specified.

7. In a gearing for machine-tools, a cone of gears, a tumbler-gear for coöoperating with the cone of gears, a shifting frame connected to the tumbler-gear, a rotary operating member, means, between the shifting frame and the operating member, for moving the frame relatively to the cone of gears, a stop, means for coacting with the stop to limit the rotation of the operating member in one direction, the last-mentioned means being movable into and out of position to coact with the stop to limit such rotation, means for moving the operating member axially in one direction during the rotation thereof and thereby bringing said last-mentioned means into position to coact with the stop to limit such rotation, and a spring for moving the operating member axially in the opposite direction, substantially as and for the purpose described. 85 90 95 100

8. In a gearing for machine-tools, a cone of gears, a tumbler-gear for coöperating with the cone of gears, a shifting frame connected to the tumbler-gear, a rotary operating member, means, between the shifting frame and the operating member, for moving the frame relatively to the cone of gears, a stop, means for coacting with the stop to limit the rotation of the operating member in one direction, the last-mentioned means being movable into and out of position to coact with the stop to limit such rotation, means for moving the operating member axially to bring said last-mentioned means into position to coact with the stop to limit such rotation, and means for preventing said axial movement of the operating member, substantially as and for the purpose described. 105 110 115 120

9. In a gearing for machine-tools, a cone of gears, a tumbler-gear for coöperating with the cone of gears, a shifting frame connected to the tumbler-gear, a rotary operating member, means, between the shifting frame and the operating member, for moving the frame relatively to the cone of gears, a stop, means for coacting with one face of the stop to limit 125

the rotation of the operating member in one direction, the last-mentioned means being movable axially into and out of position to coact with said face to limit such rotation, 5 and being movable into and out of position to coact with another face of the stop for preventing axial movement of the operating member in one direction, and means for moving the operating member axially during the rotation thereof and thereby bringing the second-mentioned means into position to coact with the first-mentioned face of the stop, substantially as and for the purpose specified.

10. In a gearing for machine-tools, a cone 15 of gears, a tumbler-gear for coöperating with the cone of gears, a shifting frame connected to the tumbler-gear, a rotary operating member, means, between the shifting frame and the operating member, for moving the frame 20 relatively to the cone of gears, means for limiting the rotation of the operating member in one direction, a stop, means on the operating member for coacting with the stop to limit the rotation of the operating member in the 25 opposite direction, the operating member being movable axially to bring said means thereon into and out of position to coact with the stop to limit the rotation of the operating member in said opposite direction, means for 30 moving the operating member axially during the rotation thereof, and means for preventing said axial movement of the operating member, substantially as and for the purpose described.

35. 11. In a gearing for machine-tools, a cone of gears, a tumbler-gear for coöperating with the cone of gears, a shifting frame connected to the tumbler-gear, a rotary operating member, means, between the shifting frame and 40 the operating member, for moving the frame relatively to the cone of gears, means for limiting the rotation of the operating member in one direction, a stop, means on the operating member for coacting with the stop to limit the rotation of the operating 45 member in the opposite direction, the operating member being movable axially to bring said means thereon into and out of position to coact with the stop to limit the rotation of the operating member in said opposite direction, means for 50 moving the operating member axially in one direction during the rotation thereof and thereby bringing said means on the operating member into position to coact with the stop to limit the rotation of the operating member in said opposite direction, a spring for 55 moving the operating member axially in the opposite direction, and means for preventing axial movement of the operating member, substantially as and for the purpose set forth.

60. 12. In a gearing for machine-tools, a cone of gears, a tumbler-gear for coöperating with the cone of gears, a shifting frame connected to the tumbler-gear, and a rotary worm for

moving the shifting frame, substantially as 65 and for the purpose specified.

13. In a gearing for machine-tools, a cone of gears, a tumbler-gear for coöperating with the cone of gears, a pivoted shifting frame connected to the tumbler-gear and provided 70 with teeth, and a rotary member coacting with the teeth for moving the shifting frame relatively to the rotary member, substantially as and for the purpose described.

14. In a gearing for machine-tools, a cone 75 of gears, a tumbler-gear for coöperating with the cone of gears, a pivoted shifting frame connected to the tumbler-gear and provided with teeth, and a rotary worm arranged with its axis at an angle to the cone of gears and 80 coacting with the teeth for moving the shifting frame relatively to the rotary worm, substantially as and for the purpose set forth.

15. In a gearing for machine-tools, a cone 85 of gears, a tumbler-gear for coöperating with the cone of gears, a shifting frame connected to the tumbler-gear, a rotary worm for moving the shifting frame, and a member for actuating the worm, said member being movable axially relatively to the worm, substantially 90 as and for the purpose specified.

16. In a gearing for machine-tools, a cone of gears, a tumbler-gear for coöperating with the cone of gears, a pivoted shifting frame connected to the tumbler-gear and provided 95 with teeth, a rotary worm arranged with its axis at an angle to the cone of gears and coacting with the teeth for moving the shifting frame relatively to the rotary worm, and a rotary member for actuating the worm, said 100 member being arranged with its axis substantially coincident with the axis of the worm and being movable axially relatively to the worm, substantially as and for the purpose described.

17. In a gearing for machine-tools, a cone of gears, a tumbler-gear for coöperating with the cone of gears, a shifting frame connected to the tumbler-gear, a rotary worm for moving the shifting frame, a rotary member for actuating the worm, and means for moving 110 said member axially during the rotation thereof, substantially as and for the purpose set forth.

18. In a gearing for machine-tools, a cone 115 of gears, a tumbler-gear for coöperating with the cone of gears, a shifting frame connected to the tumbler-gear, an operating member movable along the cone of gears, and means, between the shifting frame and the operating 120 member, for moving the frame with the operating member along the cone of gears, and for moving the frame relatively to the operating member in a direction at an angle to the axis of said cone of gears, substantially 125 as and for the purpose specified.

19. In a gearing for machine-tools, a cone of gears, a tumbler-gear for coöperating with

the cone of gears, a shifting frame connected to the tumbler-gear, an operating member movable in a direction substantially parallel to the axis of the cone of gears, and means, 5 between the shifting frame and the operating member, for moving the frame along the cone of gears, and for moving the frame relatively to the operating member in a direction at an angle to the axis of said cone of gears, substantially as and for the purpose described.

20. In a gearing for machine-tools, a cone of gears, a tumbler-gear for coöperating with the cone of gears, a shifting frame connected to the tumbler-gear, an operating member movable along the cone of gears, means, between the shifting frame and the operating member, for moving the frame along the cone of gears, and means for moving the frame relatively to the operating member in a direction at an angle to the axis of the cone of gears, and during the movement of the frame along said cone of gears, substantially as and for the purpose set forth.

21. In a gearing for machine-tools, a cone of gears, a tumbler-gear for coöperating with the cone of gears, a shifting frame connected to the tumbler-gear, a rotary operating member movable along the cone of gears, means, between the shifting frame and the operating member, for moving the frame along the cone of gears, means for moving the frame relatively to the operating member in a direction at an angle to the axis of the cone of gears, and during the movement of the frame along said cone of gears, and means for moving the frame relatively to the operating member during the rotation of said member, substantially as and for the purpose specified.

22. In a gearing for machine-tools, a cone of gears, a tumbler-gear for coöperating with the cone of gears, a shifting frame connected to the tumbler-gear, a rotary operating member movable along the cone of gears, means, between the shifting frame and the operating member, for moving the frame along the cone of gears, means for moving the frame relatively to the operating member in a direction at an angle to the axis of the cone of gears, and during the movement of the frame along said cone of gears, means for moving the frame relatively to the operating member during the rotation of said member, and means for locking the operating member from rotation during the movement thereof along the cone of gears, substantially as and for the purpose described.

23. In a gearing for machine-tools, a cone of gears, a tumbler-gear for coöperating with the cone of gears, a shifting frame connected to the tumbler-gear, an operating member movable along the cone of gears and movable at an angle thereto, means, between the shifting frame and the operating member, for moving the frame with the operating member

along the cone of gears, and means for preventing the movement of the operating member along the cone of gears, the last-mentioned means being movable from its operative position by the operating member when moving at an angle to the cone of gears, substantially as and for the purpose set forth.

24. In a gearing for machine-tools, a cone of gears, a tumbler-gear for coöperating with the cone of gears, a shifting frame connected to the tumbler-gear, an operating member movable along the cone of gears, means, between the shifting frame and the operating member, for moving the frame with the operating member along the cone of gears, and for moving the frame relatively to the operating member in a direction at an angle to the axis of said cone of gears, and means for preventing the movement of the operating member along the cone of gears, substantially as and for the purpose specified.

25. In a gearing for machine-tools, a cone of gears, a tumbler-gear for coöperating with the cone of gears, a shifting frame connected to the tumbler-gear, an operating member movable along the cone of gears, and also movable axially, means, between the shifting frame and the operating member, for moving the frame with the operating member along the cone of gears, and means for preventing the movement of the operating member along the cone of gears, said means being movable from its operative position by the operating member when moving axially, substantially as and for the purpose described.

26. In a gearing for machine-tools, a cone of gears, a tumbler-gear for coöperating with the cone of gears, a shifting frame connected to the tumbler-gear, a rotary operating member movable along the cone of gears, and also movable axially, means, between the shifting frame and the operating member, for moving the frame along the cone of gears, means for moving the frame relatively to the operating member in a direction at an angle to the axis of the cone of gears, and during the movement of the frame along said cone of gears, means for moving the frame relatively to the operating member during the rotation of said member, and means for preventing the movement of the operating member along the cone of gears, said means being movable from its operative position by the operating member when moving axially, substantially as and for the purpose set forth.

27. In a gearing for machine-tools, a cone of gears, a tumbler-gear for coöperating with the cone of gears, a shifting frame connected to the tumbler-gear, a rotary operating member movable along the cone of gears, and also movable axially, means, between the shifting frame and the operating member, for moving the frame along the cone of gears, means for moving the frame relatively to the operating

member in a direction at an angle to the axis of the cone of gears, and during the movement of the frame along said cone of gears, means for moving the frame relatively to the operating member during the rotation of said member, means for preventing the movement of the operating member along the cone of gears, said means being movable from its operative position by the operating member when moving axially, and means for limiting the rotation of the operating member, substantially as and for the purpose specified.

28. In a gearing for machine-tools, a cone of gears, a tumbler-gear for coöperating with the cone of gears, a shifting frame connected to the tumbler-gear, a rotary operating member movable along the cone of gears, and also movable axially, said member being formed with an annular groove and with a lengthwise passage opening through one side of the groove, a stop normally projecting into the groove and arranged at one side of the passage, means carried by the operating member and coacting with the stop to limit the rotation of the operating member and thereby align the passage with the stop for permitting the movement of the stop into the passage upon the axial movement of the operating member, and means for preventing the movement of the operating member along the cone of gears, said means being movable from operative position when the operating member is moved axially, substantially as and for the purpose described.

35. 29. In a gearing for machine-tools, a cone of gears, a tumbler-gear for coöperating with the cone of gears, a shifting frame connected to the tumbler-gear, a case, a carriage guided by the case, and means, between the shifting frame and the carriage, for moving the frame along the cone of gears and for moving the frame relatively to the carriage in a direction at an angle to the axis of said cone of gears, substantially as and for the purpose set forth.

45. 30. In a gearing for machine-tools, a cone of gears, a tumbler-gear for coöperating with the cone of gears, a shifting frame connected to the tumbler-gear, a case, a carriage guided by the case and connected to the shifting frame for moving the latter, an operating member journaled in the carriage, and means, between the operating member and the shifting frame, for moving the frame relatively to the operating member, substantially as and for the purpose specified.

31. In a gearing for machine-tools, a cone of gears, a tumbler-gear for coöperating with the cone of gears, a shifting frame connected to the tumbler-gear, a case, means supported by the case and movable in a direction substantially parallel to the axis of the cone of gears and movable in a direction at an angle to said axis, and means connecting the

shifting frame to the first-mentioned means, 65 substantially as and for the purpose described.

32. In a gearing for machine-tools, a cone of gears, a tumbler-gear for coöperating with the cone of gears, a shifting frame connected to the tumbler-gear, a slide movable along the cone of gears and also movable at an angle thereto, said slide being connected to the shifting frame for moving the same along the cone of gears, and means carried by the 75 slide for moving the shifting frame relatively to the slide, substantially as and for the purpose set forth.

33. In a gearing for machine-tools, a case having a bearing-face, a cone of gears, a 80 tumbler-gear for coöperating with the cone of gears, a shifting frame connected to the tumbler-gear and provided with teeth spaced apart from the bearing - face, a carriage guided by the case along the cone of gears, a 85 slide movable with the carriage and movable relatively thereto at an angle to the axis of the cone of gears, the slide bearing against said face of the case, and a rotary worm movable with the slide and coacting with the 90 teeth of the shifting frame, substantially as and for the purpose specified.

34. In a gearing for machine-tools, a case having a bearing-face, a cone of gears, a tumbler-gear for coöperating with the cone 95 of gears, a shifting frame connected to the tumbler-gear and provided with teeth spaced apart from the bearing - face, a carriage guided by the case along the cone of gears, a slide movable with the carriage and movable 100 relatively thereto, the slide bearing against said face of the case, a rotary worm movable with the slide and coacting with the teeth of the shifting frame, and a rotary operating member for the worm, said member being 105 journaled in the carriage and the slide and extending axially relatively to the worm, substantially as and for the purpose described.

35. In a gearing for machine-tools, a cone 110 of gears, a tumbler-gear for coöperating with the cone of gears, a shifting frame connected to the tumbler - gear, a carriage movable along the cone of gears, a slide movable with the carriage and movable relatively thereto 115 at an angle to the cone of gears, said slide being connected to the shifting frame for moving the same along the cone of gears, a worm movable with the slide and connected to the shifting frame for moving the same relatively to the slide, an operating member journaled in the carriage and slide and extending axially relatively to the worm, 120 means for limiting the rotation of the operating member in either direction, means for moving the operating member axially in one direction, a spring for moving the operating member axially in the opposite direction,

means for preventing the movement of the carriage, connections between the last-mentioned means and the operating member for moving said means from operative position
5 when the operating member is moved axially in one direction, and means for locking the operating member from rotation during the movement of the carriage, substantially as and for the purpose set forth.

In testimony whereof I have hereunto signed my name, in the presence of two attesting witnesses, at Syracuse, in the county of Onondaga, in the State of New York, this 2d day of February, 1906.

WILLIAM RUNGE.

Witnesses:

S. DAVIS,
E. K. SEEMILLER.
